US00D887786S

(12) **United States Design Patent** (10) **Patent No.:** **US D887,786 S**
(45) **Date of Patent:** **** Jun. 23, 2020**

(54) **REUSABLE SEALABLE BOWL**

- (71) Applicant: **Rebecca Finell**, Austin, TX (US)
(72) Inventors: **Rebecca M. Finell**, Austin, TX (US);
Joshua J. Nelson, Mesa, AZ (US)
(73) Assignee: **FINELL CO., LLC**, Austin, TX (US)
(**) Term: **15 Years**
(21) Appl. No.: **29/618,115**
(22) Filed: **Sep. 19, 2017**
(51) LOC (12) Cl. **07-07**
(52) U.S. Cl. **USPC D7/602**
(58) **Field of Classification Search**
USPC D7/601, 602; D9/430; 426/85
CPC A47G 19/02; A47G 19/025
See application file for complete search history.

(57) **CLAIM**

The ornamental design for a reusable sealable bowl, as shown and described.

DESCRIPTION

FIG. 1 illustrates a perspective top/front view of a reusable sealable bowl, showing the new, original and ornamental design, wherein the bowl is open and unsealed.

FIG. 2 shows a perspective bottom/front view of the reusable sealable bowl shown in FIG. 1.

FIG. 3 shows a side view of the reusable sealable bowl shown in FIG. 1.

FIG. 4 shows a front view of the reusable sealable bowl shown in FIG. 1.

FIG. 5 shows a bottom view of the reusable sealable bowl shown in FIG. 1.

FIG. 6 illustrates a perspective top/front view of the reusable sealable bowl shown in FIG. 1, showing the new, original and ornamental design, wherein the bowl is closed and sealed.

FIG. 7 shows a perspective bottom/front view of the reusable sealable bowl shown in FIG. 6.

FIG. 8 shows a side view of the reusable sealable bowl shown in FIG. 6.

FIG. 9 shows a front view of the reusable sealable bowl shown in FIG. 6; and

FIG. 10 shows a bottom view of the reusable sealable bowl shown in FIG. 6.
